UNITED STATES PATENT OFFICE.

EDOUARD F. D. DEBOUTTEVILLE, OF ROUEN, FRANCE.

MACHINE FOR SHAPING, DRILLING, BORING, AND FACING METALS.

SPECIFICATION forming part of Letters Patent No. 275,604, dated April 10, 1883.

Application filed April 6, 1882. (No model.) Patented in France April 25, 1881, No. 142,510; in England May 3, 1881, No. 1,910, and in Germany May 6, 1882, No. 16,381.

To all whom it may concern:

Be it known that I, EDOUARD FRANÇOIS DELAMARE DEBOUTTEVILLE, a citizen of the Republic of France, and a resident of Rouen, Seine Inférieure, France, have invented a certain Improved Machine for Shaping, Drilling, Boring, and Facing Metals, (for which French Letters Patent No. 142,510, April 25, 1881, and British Letters Patent No. 1,910, May 3, 1881, have been granted,) of which the following is a specification.

My invention relates to certain improvements in the construction of metal-working machines; and it consist in so constructing the machine that the article to be operated on, when once placed in position, may be drilled, bored, slotted, milled, planed, surfaced, and otherwise finished without being removed from the work-table. By this means the work will be executed with greater precision and in much less time than in the ordinary way with a separate machine for each operation. At the same time the machine is so constructed as to insure a firm rigidity of the parts, and thereby obtain perfect regularity in the work done.

In the accompanying drawings, Figure 1, Sheet 1, represents a side view of my machine; Fig. 2, Sheet 3, a rear elevation; Fig. 3, Sheet 2, a sectional plan on the line 3 4, Fig 4; Fig. 30, Sheet 2, a vertical section on the line 1 2, Fig. 3; Fig. 5, Sheet 4, a front elevation, partly in section; Figs. 6 and 7, Sheet 3, enlarged sectional views of a part of the operating devices of the machine; and Figs. 5bis, 8, and 9, 35 detached views of parts of the apparatus.

A is a horizontal bench bolted to the base-plate B, which is cast in one piece with a standard, B'. The upper part of this standard is curved over and terminates in two ex-40 tensions, a, which serve as guides to a vertical slide, C.

To guides on the horizontal bench A is adapted a saddle or carriage, C', to which a longitudinal motion on the bench may be im-45 parted, as hereinafter described; and this saddle C' is provided with guides at right angles to those of the bench A, and on these guides is mounted a second carriage, D, to which a transverse motion may be imparted. On this 50 second carriage D is mounted a table, p, which

is adapted to be rotated in a horizontal plane by the devices hereinafter described, and on which the work to be done is placed and secured.

The lower end of the slide C carries a tool-holder, O, which may be of the ordinary construction. The slide also carries a vertical spindle, g, to which the drilling and similar tools are secured, and to which a rotary motion may be imparted, as hereinafter described. 55 Washers o o' are provided to compensate for the wear on the shoulders or collars on the spindle g, bearing against the bearings in the slide C.

The principal portion of the driving-gear is 65 arranged in the rear of the standard B', and the machine may be driven by a belt passing over a cone-pulley, P, the shaft of which carries a bevel-wheel, r, and pinion p', for transmitting power to different parts of the ma-70 chines. Thus the rotary motion of the pinion p' is transmitted (Fig. 4) through the gear-wheels e f', bevel-wheels h h', and gears i and j to the tool-spindle g when the wheel f' is made fast to its shaft by the screw d'. The 75 upper end of the spindle g passes through the wheel j, and is provided with a feather, so that while it can slide freely through the wheel in partaking of the vertical motion of the slide C, Fig. 4, the tool-spindle rotates when the 80 wheel j is rotated.

The miter-wheel r transmits motion, when desired, through the bevel-wheels k, l, and M, Fig. 4, to the carriages C' D and table p, car-85 rying the work.

The main shaft, carrying the driving-pulley P, also carries a pulley, p², Figs. 3 and 4, which, through the intermediate belt-pulleys, r' r², Figs. 1, 2, 3, and 5, drives the pulley E for operating the differential movement on the shaft 90 G, Fig. 1, as more fully described hereinafter.

Having now briefly referred to some of the principal operating parts of the machine, I will proceed to describe in detail the separate parts: first, the bench, sliding carriages, work-table, and accessories; secondly, the tool-car-95 rying slide and its parts; and, thirdly, the different adjustments and operations of the machine for the various classes of work to be done.

I. *The work-table.*—As indicated above, the work-table may have three different motions imparted to it in a horizontal plane: first, a longitudinal motion by the movement of the carriage C' on the bed; second, a transverse motion by the movement of the carriage D on the carriage C'; and, third, a rotary motion of the table on the carriage D. The longitudinal motion of the carriages and table on the bench 5 may be either slow or fast, according to the nature of the work (milling or planing) to be done. The slow longitudinal motion is imparted to the carriages by means of a screw-shaft, V, mounted in bearings in the bench A, 10 and carrying at its outer end a band-pulley, g', which is loose on the end of the screw-shaft, but may be fixed thereto by screwing up the tightening-nut r', which jams the pulley against a shoulder on the screw-shaft V, as shown in 15 Fig. 1. This convenient construction of coupling has the advantage of rendering the dismounting of any of the parts to stop the motion unnecessary, and permits a rapid change from mechanical to hand power when necessary, the 20 end of the screw-shaft being provided with a crank-handle for the purpose. This coupling possesses the further advantage of permitting the automatic stoppage of the movement of the screw V should any unusual obstruction be presented to the tool, for then the frictional clamping action of the wheel v' will not be sufficient to prevent the pulley g' from slipping on the shaft V. The shaft V passes between the two 25 parts of a nut, d d, Fig. 5, which is guided in lugs projecting from the under side of the carriage C'. The two parts of this nut may be brought together and into gear with the screw-shaft, or separated and out of gear therewith, by means of a disk, x, Fig. 5^{vis}, provided with 30 cams or eccentric slots and operated by means of a suitable handle, x', Fig. 5. A band from the pulley g' passes over a pulley, g², on the end of the horizontal shaft G, Fig. 3, to which a rotary motion is imparted by the 35 ratchet-wheel l' or differential motion operated by the pulley E, as hereinafter described, so that when the pulley g' is secured to the end of the screw-shaft and the two-part nut d put into gear with the screw-shaft V a rotary motion will be imparted to the latter, and consequently a longitudinal movement to the carriage and work-table. When it is desired to impart a more rapid longitudinal reciprocating motion to the carriages and table, 45 the two-part nut d is separated out of gear with the screw-shaft and the pulley g' set free thereon, and an adjustable connecting-rod, H, pivoted to the carriage C' at a', Fig. 4, is attached to a crank-pin secured to the face of 50 the driving-wheel M, this crank-pin being adjustable in radial guides in the latter to the proper position for giving the desired extent of travel of the carriages and the work on the bench. The desired transverse motion of the 55 carriage D on the carriage C' is obtained through the medium of a screw-shaft, r, Figs. 3, 4, and 5, which is adapted to bearings l³ in the carriage C', and passes through a threaded socket secured to the under side of the carriage D. Rotary motion may be imparted to the screw-shaft v from the shaft G through the medium of the bevel-wheels l' m, Fig. 5, pinion n, and gears o² p³, Figs. 1 and 3. The bevel-wheel l' is connected to the shaft G by a groove and feather, so that while it turns 60 with the shaft it can slide thereon longitudinally. To the under side of the table p is secured a worm-wheel, x², into which gears a worm, x³, Figs. 4 and 5, keyed on a transverse shaft, t, adapted to bearings in brackets 65 projecting from opposite sides of the carriage C'. On the end of this shaft t is a pinion, q, which gears into and is driven by the pinion o², before referred to. Each of the pinions p³ and q is normally loose on its shaft, 70 but can be clamped thereto by a screw-clamp similar to that v' for the pulley g', and each shaft v and t is provided with a crank, by which it may be turned by hand. At the opposite end of the shaft t from the pinion q is a 75 dividing-plate, Q, hereinafter referred to, and the bearing for the said shaft t, adjacent to this dividing-plate, is provided with a binding-screw, t', Fig. 8, by which the shaft may be secured in any position and prevented from turning 80 while the machine is being used for planing, drilling, &c. The opposite bracket-bearing for the shaft t is adjustably secured to the carriage C', so as to allow for compensation for wear of the worm-wheel and worm. The dividing-plate Q, which, as shown in Figs. 8 and 9, is mounted on a sleeve secured to the bracket-bearing, has, say, one thousand divisions marked on it. It is provided with an annular undercut or T-shaped recess, to which are 85 adapted buttons or stops m' m². The first button, m', always remains fixed at zero, while the other, m², is adjusted away therefrom, according to the number of divisions it is intended to mark on the work. A handle or 90 pointer, M', to move between these two points, can be made fast or loose on the shaft t by means of a gripping collar and cam, c², to provide for turning the table p through the screw x³ the extent of one division at a time. The 95 differential movement, by means of which the shaft G may be run fast or slow or left loose, is shown in detail in Figs. 6 and 7. A pulley, E, mounted loosely on the shaft G and driven by belts from the pulleys r' r², is provided 100 with a fixed radial axle, on which is mounted a bevel-wheel, c'. This bevel-wheel, which may be allowed to run free on its axis or be fixed thereto by a set-screw, z, gears on one side into a bevel-wheel, n', keyed to the shaft 105 G, and on the other with a bevel-wheel, c', mounted loosely on a fixed sleeve, in which the shaft G turns. The bevel-wheel c' may be made fast to its sleeve by means of a friction screw-coupling, v², similar to those above referred to. To run the shaft G at a moderately slow speed, the wheel e' is secured to its 110

fixed axle by the set-screw z , and the coupling v^2 loosened, so that the pinion n' , which is keyed to the shaft G , will turn at the same speed as the pulley E . To increase the speed the screw z is loosened and the coupling v^2 screwed up, so that the pinion n' and shaft G will run at twice the speed of the pulley. By loosening both the coupling v^2 and screw z the pulley E will run loose on the shaft G and the latter be free to be rotated by other means independent of those described. In the drawings I have shown a pawl and ratchet for imparting an intermittent rotary motion to the shaft G . The pawl k^2 of this ratchet k' is carried by one end 15 of a pivoted lever, k^3 , Fig. 7, the opposite end of which is connected by the link k^4 to an eccentric, f , on the shaft F of the wheel M . The table p , carrying the work, can thus be moved in all directions horizontally below the 20 tools at different speeds, and either by mechanical or hand power, according to the requirements of the work to be done.

II. The tool-carrying slide.—The tool-carrying slide C can have a vertical motion imparted 25 to it on guides on the standard, and this motion may be either simply for adjustment or slow or rapidly reciprocating, according to the work to be done. The cutting-tool, say for planing, is fixed in the block b on the tool-holder O , carried by the lower end of the slide, and constructed in the usual manner, so as to tip or yield on the return-stroke. The tool-holder O is provided with a toothed sector and worm b' , by which any desired inclination may 30 be given to the holder O . At the back of the slide is a helicoidal rack, H' , Figs. 3 and 4, into which gears the worm h^2 , mounted in bearings in the lever L . This lever is pivoted at its outer end to the standard B' , and may be 35 moved by hand, so as to throw the worm h^2 into or out of gear with the rack, as required, and it is held in either position indicated by dotted lines in Fig. 3 by means of a sliding bolt or catch, i' , as shown in Fig. 5. On the 40 lower end of the axis of this worm is a pinion or ratchet-wheel, into which takes a pawl on a second pivoted lever, L' , below the lever L . By the horizontal vibrating motion of this lever L' on its pivot the ratchet is intermittently 45 rotated, and through it the worm h^2 is rotated, and the latter, acting on the rack H' , causes the slide C to rise or descend, as may be required. This horizontal vibrating motion may be imparted to the lever L' to operate the 50 slide either by hand or mechanically. In the latter case the lever L' is connected by rods l^2 and lever l^3 to an eccentric on the axle F of the wheel M . When it is desired to give a 55 rapid vertical reciprocating motion to the slide C , as for slotting, the slide is connected by the rod P' with the crank-disk P^2 , which is mounted on the same shaft as the gear-wheel e , Fig. 4. The length of stroke or extent of movement of the slide can be regulated by adjusting the 60 crank-pin in a radial slot in the disk P^2 . The vertical spindle g , which, as before described,

is mounted in bearings in the slide C , and can be rotated from the pinion p' by the gearing e , f' , h , h' , i , and j , is adapted to receive a suitable metal-working tool, such as a boring-bit or a milling-tool. To complete the machine a rotary cutting-tool, s , for cutting wheels or dividing, is provided, this tool being carried by a support, S , Figs. 3 and 4, to which an up-and-down motion on slides can be given by a 70 suitable pivoted lever. (Not shown in the drawings.) The support may be so constructed and adapted to its slides that a slight inclination may be given to it when desired. The rotary cutting-tool is driven by a belt or band 75 from some moving part of the machine, as indicated by dotted lines in Figs. 3 and 4 for instance.

III. Operations.—The different adjustments of the various parts for carrying out the different operations of which the machine is capable will now be briefly described.

For planing.—The carriage C' is connected to the crank-pin on the rotating wheel M by the connecting-rod H , so as to impart a rapid 90 horizontal to-and-fro motion to the carriages, work-table, and work beneath the cutting tool in the holder O , the slide C having been adjusted to the proper height. The necessary transverse intermittent feed motion of the 95 work after each cut is effected by the action of the screw-shaft v on the carriage D , this screw-shaft receiving its motion from the shaft G through the gearing above described, and the shaft G being acted on by the pawl k^2 and 100 ratchet k' , while all the other movements are thrown out of gear. The cutting-tool is fixed in the block b by screws, and a small spiral spring, Fig. 4, is employed to bring the tool to its cutting position after each stroke. 105

Turning and boring.—The pinion q is clutched to its shaft t and the differential movement so adjusted that the pinion n' and shaft G run at the same speed as the pulley, and the shaft G transmits rotary motion to the shaft t , and thence by the worm x^3 to the table p on the carriage D . The turning or boring tool is fixed in the holder O , and the slide C is caused to descend slowly by the action of the lever L' and its pawl (operated by hand or automatically) on the ratchet of the worm h^2 , which 110 gears into the rack on the back of the slide. The other movements, during this operation, are of course thrown out of gear. 115

Drilling.—The carriages C' and D and table p are fixed with the work in position under the spindle g . The gear-wheel f' , which at other times is allowed to run loose on its shaft, is now fixed thereto by its screw d' , so that a rapid rotary motion through the gearing above 120 described is imparted to the spindle g , to which the drilling-tool is secured. The requisite downward pressure of the spindle and tool is obtained by causing the pawl-lever L' to depress the slide C , as before described. 125

Slotting.—For this purpose the slotting-tool is fixed in the holder O by the usual screws, 130

and the tipping motion of the block, which is used in planing, prevented by means of the screw v , Fig. 4. The slide C is connected to the crank-pin on the rotating disk P^2 through the medium of the connecting-rod P' , so as to impart a vertical reciprocating motion to the slide and tool. The necessary feed motion between the strokes of the tool is imparted to the work by putting the screw V in intermittent action, so as to move the carriages and work-table longitudinally on the bench A, or by putting the screw v into action to move the carriage D and work-table transversely, according to the requirements of the slot to be cut.

Surfacing.—The surfacing-tool is fixed in the lower end of the spindle g , to which a rotary motion is imparted by the means above described, and the slide C may be caused to descend slowly, or may be held at any desired height. The work-table may be moved in any direction horizontally by the devices before described, according to the form of the work to be surfaced.

Dividing or wheel-cutting.—The rotary cutting-tool is fixed to the carrier s of the adjustable support S and motion communicated to the tool by belts, and the table p is adjusted to a position within range of the tool, and after each cut is moved or adjusted for the next cut by means of the handle M' , Figs. 5, 8, and 9, of the divider Q, which handle has been clamped to the end of the shaft t for the purpose. The foregoing are the principal operations which can be effected on this machine, whereby the most complicated pieces of work may be finished without being removed from the machine.

I claim as my invention—

- 40 1. In a metal-working machine, the combination of a bed-plate and movable work-table with a standard, a slide carrying a cutting-tool, and a drill-spindle mounted in bearings in said slide, and mechanism, substantially as described, for reciprocating the slide and for rotating the spindle.
2. The combination of the bed-plate, carriages C' and D, and work-table with rotary feed-screw V, driving-wheel M, and connect-

ing-rod H, and devices, substantially as set forth, for putting the feed screw or wheel into operative gear with the carriages, for the purpose described.

3. The combination of the movable table or carriage with a feed-screw shaft having a shoulder thereon, an operating-wheel on the shaft adjacent to the shoulder, and a screw-clamp, whereby the said wheel may be clamped to or released from the said shaft.

4. The combination of the bed-plate and traversing carriages, work-table, and feed-screws with a shaft, G, for operating said feed-screws, gear-wheels, and clamps for securing the said wheels to and releasing them from the feed-screws, substantially as described.

5. The combination of the movable work-table of a metal-working machine with a shaft, G, for imparting motion thereto, and a driving-pulley, E, on said shaft, gear-wheels $e' n' c'$, and devices, substantially as described, for locking the wheels $e' c'$ on their axes or releasing them therefrom, as and for the purpose set forth.

6. The combination of a driven shaft, G, with a pulley, E, loose thereon, and carrying a radial axis and gear-wheel, e' , a gear-wheel, n' , secured to the shaft, sleeve, and gear-wheel c' , and retaining devices for securing the wheel e' to its axis and the wheel c' to its sleeve, substantially as specified.

7. The combination of a movable work-table and standard with a slide carrying a cutter-holder and drill-spindle, gearing for rotating the spindle, crank and connecting-rod for reciprocating the slide, and rack and worm for adjusting the slide.

8. The combination of the standard and tool-slide, having a rack, H' , with a worm, L, carried by a lever, and a pawl and pinion for operating said worm, all substantially as described.

In testimony whereof I have signed my name to this specification in the presence of two subscribing witnesses.
